UNITED STATES PATENT OFFICE.

ELMER A. WATTS AND EDWARD G. MORRISON, OF SPRINGFIELD, OHIO.

GAS-ENGINE.

No. 872,598.

Specification of Letters Patent.

Patented Dec. 3, 1907.

Application filed January 12, 1906. Serial No. 295,692.

To all whom it may concern:

Be it known that we, ELMER A. WATTS and EDWARD G. MORRISON, citizens of the United States, residing at Springfield, in the county of Clark and State of Ohio, have invented certain new and useful Improvements in Gas-Engines, of which the following is a specification, reference being had therein to the accompanying drawings.

10 This invention relates to gas engines, and to other explosive engines of the same general type, and has for its object to provide a construction whereby the regulation of the speed of the engine may be effected through 15 the making and breaking of the electric circuit of the ignition device, provision being further made to economize the fuel by maintaining the exhaust valve closed while the ignition circuit is thus broken, so as to prevent 20 the drawing in and expulsion of the fuel charges while the igniter is thus rendered inoperative.

A further object of the invention is to dispense with the usual side shaft, gearing and 25 cams employed to transmit motion from the engine shaft and to operate the valves.

More specifically, our invention has for its object to provide a simple, compact and efficient mechanism whereby the desired results 30 above indicated may be obtained, and to these ends our invention consists in certain novel features which we will now proceed to describe, and will then particularly point out in the claims.

35 In the accompanying drawings, Figure 1 is a vertical sectional view of a gas engine embodying our invention in one form; Fig. 2 is a view of one of the fly wheels and the governor thereon; Fig. 3 is an enlarged detail 40 sectional view of the cylinder forming a part of the valve-operating apparatus; and Fig. 4 is a detail view of the contact ring which co-operates with the governor shown in Fig. 2.

In the present instance, we have chosen for 45 the purpose of illustrating the application of our invention a well known form of gas engine, but we wish it to be understood that our invention is not limited in its application to this particular form of engine.

50 In the engine chosen for purposes of illustration, 1 indicates the supporting frame, and 2 the cylinder, containing the piston 3, which, by the connecting rod or pitman 4, operates the engine shaft 5 through the 55 crank 6, said shaft being shown as having a

fly wheel 7 at each end. The engine is shown as of the vertical type.

8 indicates the igniter, which, in the present instance, is shown as an electric igniter of the jump-spark type. 60

9 indicates the inlet valve, which is an inwardly opening valve, normally closed by a spring 10, and opened by the suction of the piston during the charging stroke. Any approved valve of this type may be employed. 65

11 indicates the exhaust valve, which is also shown as an inwardly opening valve, provided with a stem 12 and held normally closed by a spring 13.

In the wall of the cylinder 2 there is formed 70 a port 14, so located that the piston just passes beyond the same at the end of its outward stroke. This port communicates through a passage 15 with an auxiliary cylinder 16, located at the side of the main cylinder 2 and preferably in a position at right angles thereto.

The cylinder 16 has an opening 17 at its inner end, through which the passage 15 establishes connection between the interior 80 of the cylinder 16 and port 14. The cylinder 16 has an opening 18, through which extends the outer or free end of the exhaust valve stem 12, in the present instance, its lower end. Directly opposite the opening 18 there is formed in the cylinder 16 an opening 19, through which extends the free end, in the present instance, the upper end, of an actuating rod 20. This rod is operated at proper intervals from the engine shaft to 90 open the exhaust valve by any suitable mechanism. In the present instance, we have shown for this purpose a rocking lever 21, to one arm of which the lower end of the actuating rod 20 is pivotally and slidingly 95 connected, the other end of said rocking lever being operated by a rod 22 from a cam or eccentric 23 on the engine shaft. The actuating rod 20 is thus reciprocated once for each revolution of the engine. The distance separating the adjacent ends of the actuating rod 20 and exhaust valve stem 12 is such, however, that the former does not come into contact with the latter during its movements. The connection between the 100 actuating rod and valve stem is effected at the proper time by the mechanism which we will now proceed to describe.

Within the cylinder 16 there is located a piston 24, having formed therein a slot 25, 110

extending therethrough in the direction of the plane of movement of the valve stem 18 and actuating rod 20, the valve stem normally extending into this slot and the actuating rod moving into the same when traveling toward the valve stem. Within this slot there is located a connecting or transmission block 26, which fits and slides in the slot in a direction at right angles to the line 10 of travel of the piston, which is vertically in the present instance. This block is of a length such that it can pass between the end of the valve stem 12 within the cylinder 16 and the opposite wall of said cylinder, and 15 its relations with the piston 24 are such that it travels in unison with said piston. Any approved construction may be employed to this end, but that which we prefer is the construction shown, in which the piston 24 20 is composed of two parts, having a supplemental portion 27, provided with a stem or rod 28, guided through a suitable aperture in the removable outer head 29 of the cylinder 16 and extending into the groove 25 in 25 the body of the piston 24 so that its inner end 30 forms a guide for one side of the connecting block 26, the opposite guide being formed by the end wall 31 of the slot 25. Springs 32 and 33 act upon the opposite 30 ends of the piston, counterbalancing each other and holding the piston normally in the position shown in the drawings. The spring 32 bears against the inner head of the cylinder 16 and against the adjacent end of the 35 body proper of the piston 24, while the spring 33 is coiled around the outer portion of the stem 28, bearing at one end against the supplemental portion 27 of the piston and at the other end against the head 29 of 40 the cylinder 16. The cylinder 16 is provided with an exhaust passage 34, communicating with one end of the cylinder through a port 35, normally closed by the piston 24, and with the other end of the 45 cylinder by a port 36, normally open, said exhaust passage communicating with the atmosphere or any other suitable outlet through a port 37.

Referring to the structural features thus 50 far described, it will be seen that, when the engine is running under normal conditions, said engine being an engine of the four cycle type, during the first or charging outstroke of the piston 3, the charge is drawn in 55 through the inlet valve 9 in the usual manner, and when the piston passes and uncovers the port 14, there being no pressure in the cylinder 2, the piston 24 in the cylinder 16 is unaffected, and remains in the position 60 shown, in which the connecting or transmission block 26 lies at one side of the path of the actuating rod 20, and this latter moves into the slot 25 in said piston without affecting the exhaust valve. It should be noted in 65 this connection that the extreme limit of

this inward movement of the actuating rod 20 is such as to prevent it from coming into contact with the inner end of the stem or rod 28, which now lies in its path. During the next movement of the main piston 3, which 70 is its first inward or compression stroke, the piston 24 remains quiescent, and the actuating rod 20 moves outward again, withdrawing from the slot 25. The next outward stroke of the main piston 3 occurs after 75 ignition and explosion of the charge, and pressure therefore exists within the main cylinder 2. When the main piston 3 is moved outward far enough to uncover the port 14, the gases under pressure pass 80 through said port and through the passage 15 and cylinder opening 17 into the cylinder 16, where they act upon the piston 24, and move it toward the right of Figs. 1 and 3, thereby bringing the connecting or transmission block 26 into the path of the actuating rod 20 and exhaust valve stem 12. At the beginning of the last inward stroke of the main piston 3, which is an exhaust stroke, the actuating rod 20 again moves inward into 90 the slot 25, and, coming into contact with the connecting or transmission block 26, moves it against the adjacent end of the exhaust valve stem, and thereby transmits motion to said stem and valve, opening the 95 exhaust valve to permit the discharge of the burned gases. At the termination of this stroke, the actuating rod is withdrawn, the exhaust valve is closed by the action of its spring 13, and the piston 24 is moved back 100 to its original position by means of the spring 33, thus again moving the connecting block out of the path of the actuating rod. Thereupon the same cycle of operations occurs.

It will be noted that the port 36 and exhaust passage 34 permit the air to escape from in front of the piston 24 in the cylinder 16 while it is moving outward or to the right, thus preventing resistance by compression to such movement, until said piston, or, in 110 the present instance, its supplementary portion 27, has closed the port 36. This occurs before the piston reaches the end of the cylinder in that direction, so that whatever air remains in the cylinder forms a cushion for 115 the piston at the end of its movement in that direction. It will also be noted that the main body of the piston 24 will uncover the port 35 after it has moved a predetermined distance, and will thereby permit the escape 120 of any surplus pressure which may be shut in between the body of the main piston 3 and the piston 24 during the first portion of the return stroke of the main piston, while the port 14 is kept closed by the body of said 125 main piston. The spring 33 cushions the return movement of the piston 24 under the action of the spring 33, and, preferably, the body of the piston 24 is provided with a 130 stem or projection 38, which may enter and

close the aperture 17, thereby closing that end of the cylinder 16 and forming an air or gas cushion to the same end.

It will thus be seen that the construction is such that, during the normal operation of the engine, the exhaust valve is only opened once for each two inward strokes of the main piston, this result being accomplished without the employment of any shafting, gearing 10 or cams such as ordinarily required to obtain this result by motion derived from the engine shaft, thereby materially reducing the cost of the machine by its increased simplicity, and increasing its efficiency.

15 It will be noted that the construction just described is such that the exhaust valve is opened to permit the escape of the contents of the main cylinder only after an explosion in said cylinder. We utilize this fact in the 20 governing of the engine by employing a governor which controls the igniter in such a way as to prevent ignition upon any undue increase in speed, and by reason of this, when the igniter is thus rendered inoperative 25 during excessive speed, the engine no longer draws in and exhausts fresh charges, thus wasting fuel, but merely compresses and permits the expansion of the same charge one or more times, until the speed 30 falls to the extent necessary to cause the governor to again render the igniter operative, whereupon this charge is exploded, and the normal operation of the engine proceeds as before. The particular type of governor 35 which we prefer for this purpose is that shown, which we have devised. This governor comprises a lever 39, fulcrumed between its ends at 40 on one of the fly wheels 1, and preferably on the inner face thereof. 40 This lever is provided with a centrifugally-acting weight 41 on one side of its fulcrum, while a centrifugally-acting spring 42 is connected to said lever on the other side of its fulcrum, as indicated at 43, the other end of 45 said spring being connected to the fly wheel at 44. The end of the lever 39 opposite to that at which the connection 43 is located is provided with a contact roller 45, which is in electrical connection in any suitable manner 50 with one part of the ignition circuit. Most usually, the entire engine forms a part of this circuit, and, in the present instance, the roller is assumed to be thus connected. 46 indicates an insulating ring or annulus, having 55 a body of insulating material with a contact plate of conducting material 47 set into and forming a part of its outer peripheral surface. This contact plate 47 is connected in any suitable manner, as, for instance, by a 60 conductor 48, with one of the terminals or points 49 of the igniter 8, the other terminal 50 of said igniter being in electrical connection with the roller 45. The ring 46 is supported in a stationary position in any suitable manner. Preferably, we mount the

said ring upon the projecting end of one of the bearings 51 of the engine shaft 5, the same being reduced, as indicated at 52, to receive said ring. Attached to the ring is a bracket 53, in which is mounted a locking 70 bolt 54, normally pressed toward the bearing 51 by a spring 55. The bearing is provided with a plurality of notches or recesses 56, indicated in dotted lines in Fig. 4, with any of which the end of the locking bolt 54 may be 75 engaged, and when in such engagement it will hold the ring 46 stationary and prevent rotation thereof. It will be seen, however, that the ring may be turned upon the bearing which constitutes its support in such a 80 way as to shift the position of the contact plate 47 and thereby cause the roller 45 to come into contact with said plate and close the ignition circuit at different periods of the stroke of the engine. The time at which 85 ignition occurs can thus be controlled by the adjustment of the contact ring 46.

In the normal operation of the engine, running at normal speed or below, which speed can be regulated in the usual manner by the 90 adjustment of the spring 42, the roller 45 is held against the periphery of the ring 46, upon which it travels, by the action of the spring 42, and, coming into contact with the plate 47 once during each revolution of the 95 engine shaft, it closes the circuit during such contact. This closing of the circuit renders the igniter operative, and when this occurs at the close of the compression stroke of the engine, an explosion is produced. The alternate circuit closings occur at the end of the 100 exhaust stroke, so that no explosion is produced. Upon an undue increase in speed, the centrifugal action of the weight 41 overcomes the opposing action of the spring 42, 105 and moves the roller 45 out of contact with the ring 46, thereby preventing the closing of the ignition circuit. When this occurs, no explosion is possible, the exhaust valve remains closed, and the same charge remains 110 in the engine cylinder, being alternately compressed and permitted to expand, until the speed falls sufficiently for the governor to again move the roller 45 into contact with the ring 46. When this contact is re-established, 115 the charge is exploded upon the first contact of the roller with the plate 47, and the normal operation of the engine begins at once, regardless of the original cycle. It will be understood, of course, that when an 120 unexploded charge is thus held in the cylinder with the igniter cut out of action by the governor, no fresh charge can be drawn in, since there is no sucking action of the engine, no minus pressure being produced in the 125 cylinder by the outward movement of the piston.

We do not wish to be understood as limiting ourselves to the precise details of construction hereinbefore described and shown 130

in the accompanying drawings, as it is obvious that these details may be varied without departing from the principle of our invention.

5 Having thus fully described our invention, what we claim as new and desire to secure by Letters Patent is:—

1. In an explosive engine of the four cycle type, the combination, with a main cylinder, 10 a piston therein, and an exhaust valve and its stem, of an auxiliary cylinder into which said valve stem enters, said cylinder communicating with the main cylinder, an auxiliary piston mounted in said auxiliary cylinder, 15 a connecting or transmission member carried by said auxiliary piston within its cylinder and movable relatively thereto, and an actuating rod reciprocated by the engine and entering said auxiliary cylinder, said auxiliary piston being normally so positioned 20 that the transmission member is out of the path of the actuating rod, and being moved by the explosive forces to a position such that said member is engaged by said rod 25 and engages the exhaust valve stem, substantially as described.

2. In an explosive engine of the four cycle type, the combination, with a main cylinder and its piston, of an auxiliary cylinder communicating therewith and provided with a piston, an exhaust valve having a stem entering said auxiliary cylinder on one side thereof, an actuating rod reciprocated by the engine at each revolution thereof and entering 30 the auxiliary cylinder on the opposite side thereof, and a transmission member carried by the auxiliary piston within its cylinder and adapted to be interposed between the actuating rod and exhaust valve stem by 35 the movement of the auxiliary piston when an explosion occurs in the main cylinder, said auxiliary piston being normally so positioned that said transmission member is out of the path of the actuating rod, substantially as 40 described.

3. In a four cycle gas engine, the combination, with a main cylinder and its piston, of an exhaust valve having a stem, and an actuating rod reciprocating in alignment therewith, 45 with, an auxiliary cylinder communicating with the main cylinder, an auxiliary piston mounted therein and slotted transversely to receive the ends of the valve stem and actuating rod, and a transmission block mounted to slide transversely of the piston in said slot, said block being moved to a position between the ends of the rod and valve stem when the auxiliary piston is actuated by an explosion in the main cylinder, substantially 50 as described.

4. In an explosive engine, an exhaust valve operating device comprising an auxiliary cylinder communicating with the main cylinder at one end and closed at the other 55 end, a piston fitting said cylinder and pro-

vided with a transmitting member movable by the piston to a position to transmit movement from an actuating rod to the exhaust valve stem, an exhaust port for the communicating end of said cylinder normally closed 70 by the piston, a cushioning exhaust port located near the other or closed end of the cylinder, a spring on one side of said piston to return the same to normal position and a cushioning spring on the opposite side of said 75 piston, substantially as described.

5. In a device of the character described, an auxiliary cylinder communicating with the main cylinder and into which the exhaust valve stem and its actuating rod enter, a two 80 part piston fitting said cylinder and having springs interposed between it and the cylinder heads on each side, the main or body portion of said piston being transversely slotted to receive the ends of the exhaust 85 valve stem and actuating rod and having a transmission block adapted to slide therein, the supplemental portion of the piston having a stem extending into the slot of the body portion and serving as a guide for the transmission block, substantially as described.

6. In an explosive engine, the combination, with a main cylinder and its piston, of an exhaust valve having a stem, an actuating rod extending in alignment therewith and 95 out of contact with the same, means for reciprocating said rod, an auxiliary cylinder connected with said main cylinder, a piston moving therein, a part actuated by said piston and adapted to be interposed between 100 said valve stem and said actuating rod to operatively connect the same when the piston in said auxiliary cylinder is moved to its outer position by an explosion in the main cylinder, substantially as described.

7. In an explosive engine, the combination, with a main cylinder and its piston, of an exhaust valve having a stem, a reciprocating rod actuated from the engine, 105 guideways arranged in alignment and adapted to receive the adjacent ends of said valve stem and said rod, and a part actuated by the explosion in said cylinder and adapted to be interposed between said valve stem and said rod to operatively connect the same, substantially as described.

8. In an explosive engine, the combination, with a main cylinder and its piston, of an exhaust valve having a stem, an actuating rod extending in permanent alignment therewith, means for reciprocating said rod, an auxiliary cylinder connected with said main cylinder, a piston moving therein, a part actuated by said piston and adapted to be interposed between said valve stem and 120 said actuating rod to operatively connect the same when the piston in said auxiliary cylinder is moved to its outer position by an explosion in the main cylinder, substantially as described.

9. In an explosive engine, the combination, with a main cylinder and its piston, of an auxiliary cylinder connected to said main cylinder and having a piston, an exhaust valve having a stem extending into said auxiliary cylinder, an actuating rod extending into said auxiliary cylinder opposite said valve stem, means for actuating said rod from the engine, and a part actuated by the 10 piston in said auxiliary cylinder to opera-

tively connect said valve stem and said actuating rod, substantially as described.

In testimony whereof, we affix our signatures in presence of two witnesses.
